UNITED STATES PATENT OFFICE.

WILLIAM ARTHUR, OF NEWARK, NEW JERSEY.

WATCHMAKER'S TOOL.

No. 851,854.

Specification of Letters Patent.

Patented April 30, 1907.

Application filed November 27, 1905. Serial No. 289,153.

To all whom it may concern:

Be it known that I, WILLIAM ARTHUR, a citizen of the United States, and a resident of Newark, in the county of Essex and State of New Jersey, have made and invented certain new and useful Improvements in Watchmakers' Tools, of which the following is a specification.

My invention relates to an improvement in watchmakers' tools, and more particularly to a device generally known and referred to in the trade as a pendant-set assembler, by which is meant, a tool or device for assembling the material usually contained in the pendant of a pendant-set watch. In watches of this character, there is usually employed in the pendant, a winding stem, one end of which is threaded into the crown, the opposite end projecting into the movement, said stem being capable of longitudinal movement within the pendant, and when in one position, is adapted to wind the movement, and when pulled outwardly to the other position, is adapted to set the movement. To hold this stem in its several positions and adjustments, a slotted spring sleeve is threaded into the pendant and held stationary therein, the ends of said spring which engage with the stem, being turned inwardly to fit in a groove formed in said stem to hold the latter in its several adjustments. By reason of the formation of the stem and spring, it is essential that some means be provided for opening or spreading the arms or sections of the spring, in order that it may be slipped over the stem to be properly assembled therewith prior to being fitted in the pendant. For this purpose a very small device is used by the watchmaker or repairer, which by reason of its small size, continually becomes lost or mislaid on the work-bench, and further, by reason of the different size stems which are employed in different size watches, it is necessary that several of these small devices be employed.

The object of my invention is to provide a device consisting of a plurality of posts or standards, constructed in a novel way and of different sizes, to accommodate the several sizes of stems, these posts or standards being mounted in a ring or base to properly hold them in their upright or working position, and whereby the material may be more easily and readily assembled than has heretofore been possible.

With these and other ends in view, the invention consists in certain novel features of construction and combinations of parts, as will be hereinafter fully described and 60 pointed out in the claim.

In the accompanying drawing, Figure 1 is a view of my improved tool. Fig. 2 is an enlarged view of one of the standards and also of a spring prior to the latter being 65 slipped thereon. Fig. 3 is a view partly in section and partly in elevation of one of the standards, having slipped thereon the spring, and showing the stem in position on said standard to allow the spring to be assembled 70 with said stem. Fig. 4 is a similar view showing the spring and stem after being assembled.

The tool or device consists of a suitable base or support A, that in Fig. 1 being illustrated 75 as a flat ring, and into which are threaded or otherwise secured the posts or standards B, one or more in number, preferably four, the upper ends b of which are reduced in diameter forming the shoulder c, this reduction in 80 size being graduated or increased in the case of the several posts. These upper reduced ends b of the posts B, are also drilled out or otherwise made hollow to a certain depth, as shown at d, these openings in the several 85 posts being graduated in size in order to accommodate the threaded ends C of the winding and setting stems D, which latter, as before described, are made of different sizes for use in the different size watches. 90

In practice, when it is desired to assemble the stem D and spring E, the latter is first slipped down over the proper size standard or post B until the shoulder e of the spring strikes the shoulder c of the post, the reduced end b of the post thereby spreading apart the ends of said spring, as clearly illustrated in Fig. 3. The threaded end C of the stem D is then inserted in the opening d of the post, the shoulder f of the stem D resting 100 upon the upper extreme end of said post B. The ends of the spring E being thus separated, the spring may now be easily and readily slipped off of the reduced end b of the post B and over and upon the stem D, as 105 illustrated in Fig. 4, after which the stem with its assembled spring, is lifted out or removed from the post B.

From the foregoing it will be understood that the invention is exceedingly simple in construction, cheap to manufacture, and that by means thereof the stems and springs 110

of different sizes may be easily and readily assembled. Furthermore, by reason of the posts and stems being securely fastened to a base, there is little or no danger of their becoming lost or mislaid, the tool in its complete form being of such a size that it can be readily seen or found on the workman's bench.

Having fully described my invention, what I claim as new and desire to secure by Letters Patent, is:—

An improved watchmakers' tool consisting of a flat annulus forming a base and having an annular series of threaded holes, posts or standards having lower ends threaded to engage said holes each of said posts having a

shoulder *c* between its ends and having the portion above said shoulders reduced in diameter, the reduced portions of the several posts being of unequal diameters, each of said posts having in its top an opening to accommodate the winding and setting stem of a watch, said openings being of different sizes, and said shoulders serving as seats for the internal shoulders of winding stem spring.

Signed at Newark, in the county of Essex, and State of New Jersey, this 23rd day of November A. D. 1905.

WILLIAM ARTHUR.
